UNITED STATES PATENT OFFICE.

LEONARD L. FERGUSON, OF CHICAGO, ILLINOIS, ASSIGNOR TO DUNTLEY PNEUMATIC SWEEPER COMPANY, OF CHICAGO, ILLINOIS, A CORPORATION OF DELAWARE.

CLEANING DEVICE.

1,099,243.

Specification of Letters Patent.

Patented June 9, 1914.

Application filed September 19, 1913. Serial No. 790,635.

To all whom it may concern:

Be it known that I, LEONARD L. FERGUSON, a citizen of the United States of America, and a resident of Chicago, county of Cook, and State of Illinois, have invented 5 certain new and useful Improvements in Cleaning Devices, of which the following is a specification.

The objects of this invention are to provide 10 a combined carpet sweeper and suction cleaning device with a brush removably mounted on a type of automatically adjustable operating mechanism designed to cause the brush to sweep lightly over a carpet 15 or other yielding surface regardless of the depth to which the supports of the device sink into such surface.

An illustrative embodiment of this invention 20 is shown in the accompanying drawing, in which—

Figure 1 is a side elevation of a cleaner including the present improvement. Fig. 2 is a fragmentary bottom plan view of the device. Fig. 3 is a detail in horizontal section 25 of the brush supporting mechanism.

The present invention is an improvement on the cleaning devices shown in applicant's copending application Serial No. 705,080, filed June 21, 1912. The said copending application shows and describes an automatically adjustable brush mechanism adapted to cause the brush to contact with the surface being cleaned, with a pressure inversely proportionate to the amount that a coöperating suction nozzle assists in supporting the device. The brush was not, however, readily removable for the purpose of making the device of said application exclusively a suction cleaner. The present invention employs substantially the same brush operating mechanism as the former devices, but still provides a construction whereby the brush may easily be removed.

The general arrangement of the device is 45 shown in Fig. 1. It consists of a body structure made in two parts 1 and 2. The upper part 1 is surrounded by a suitable casing 3 inclosing a plurality of suction bellows (not shown) but operated by pitman connections 50 4 to supporting wheels 5 journaled in brackets 6 extending downwardly from the body part 1. The part 1 of the device also includes means for filtering dust from the air drawn through the device by the bellows. 55 The part 2 supports a hollow suction nozzle

7 in communication with the filtering means, and also supports brush operating mechanism 8 mounted on each side of a suitable dust box 9. The parts 1 and 2 of the device are connected together with a yoke 10 having a swiveled connection 11 with the part 1, and adapted to engage spring clips 12 secured to nozzle 7. In this manner the device is rigidly held together as a unit but the parts 1 and 2 may be separated by rocking yoke 10 upwardly around its pivots 11, and by so doing permit access to the filtering device and the dust box for the purpose of removing the accumulated dust from the machine.

The brush operating mechanism is supported at each side of the machine by brackets 13 secured to the brush box 9 by screws at its ends 14 and 15. A lever 16 is located on the inside of each bracket 13 and has a pivotal connection 17 with the bracket. At their right hand ends, Figs. 1 and 3, the levers 16 are provided with horizontal slots 18 through which pass the ends of a rod 19 upon which are journaled supporting wheels 20 normally urged by springs into contact with rollers 22 secured to the brush shaft 23. The rod 19 is also arranged to resiliently exert a downward pressure on the wheels 20, or springs 30 may be provided for this purpose. Holes 24 are drilled into the ends of the shaft 23, so that the brushes 32 may be rotatably supported on pins 25 carried by leaf springs 26 and extending through slots 27 and 28 respectively in the brackets 13 and levers 16. The leaf springs 26 are pivoted to the brackets 13 by rivets 29, and the slots 27 and 28 are so arranged in the brackets 13 and lever 16 as to permit the lever 16 to rock around its pivot 17 while the leaf spring 26 rocks around its pivot 29 without altering the pressure between supporting wheels 20 and rollers 22. The ends 33 of the leaf springs 26 are so arranged as to be convenient for an operator of the device to take hold of, for the purpose of pulling the springs outwardly and thereby disengaging the brush from its supports.

In the normal operation of the device over a hard surface, the device is supported by the wheels 5 and 20, while the brush and suction nozzle lightly contact with such surface, or the nozzle 7 may be slightly above the surface being cleaned, but pressure applied to the device through the operating

handle compresses spring 30 while the pivots 17 lower and rock levers 16 so as to force the brush to bear against said surface. When the device is used to clean soft material, 5 such as various kinds of carpets and rugs, the wheels 20 will sink downwardly into the material and a large part of the weight of the device is borne by suction nozzle 7, as the latter has a large contacting surface area 10 as compared with the contacting surface of the wheels. The brush 32 therefore is not carried so far downwardly as when the wheels 20 are engaged with a hard surface, but merely lightly engages the surface of the 15 rug being cleaned without disturbing much of the nap or pile.

If it is desired to use the device simply as a suction cleaner, the brush 32 may be removed by pressing the ends 33 of the leaf 20 springs 26 outwardly, thereby withdrawing pins 25 from the recesses 24 and permitting the brush to be removed.

Although but one specific embodiment of this invention has been herein shown and described, it will be understood that some of the details of the construction shown may be altered or omitted without departing from the spirit of this invention as defined by the following claims.

30 I claim:

1. In a device of the class described, the

combination with a body, of a lever having a pivotal connection with said body, a supporting wheel journaled on the lever at one side of its pivot, a rotative brush on the 35 other side of the pivot and arranged to be driven by the wheel on said lever, means whereby the brush is removably supported by said lever, and resilient means for urging said lever to rock around its pivot in a 40 direction to carry said wheel downwardly and the brush upwardly.

2. In a device of the class described, the combination with a body, of a bracket extending outwardly from the side of said body, and having a slot therein, a lever pivotally supported on the inner side of said bracket and having a hole opposite said slot, a brush shaft having a recess in its end in alignment with said hole, a leaf spring pivoted on the outside of said bracket and provided with a pin passing through said slot and hole and into the recess in said shaft, whereby the shaft is removably connected to the lever, and a supporting wheel journaled 55 on said lever and adapted to drive said shaft.

Signed at Chicago this 16th day of September 1913.

LEONARD L. FERGUSON.
